UNITED STATES PATENT OFFICE.

SAMUEL TROOD, OF HAYSVILLE BOROUGH, PENNSYLVANIA, ASSIGNOR TO PEOPLES NATURAL GAS COMPANY, OF ALLEGHENY COUNTY, PENNSYLVANIA, A CORPORATION OF PENNSYLVANIA.

DEVICE FOR THE COMBUSTION OF LIQUID FUEL.

Application filed February 4, 1922. Serial No. 534,244.

To all whom it may concern:

Be it known that I, SAMUEL TROOD, a citizen of the United States, residing at Haysville Borough, in the county of Allegheny and State of Pennsylvania, have invented a new and useful Improvement in Devices for the Combustion of Liquid Fuel, of which improvement the following is a specification.

My invention relates to improvements in devices for the combustion of liquid fuel. The object is to produce a device of this character in which cheapness and simplicity in construction is attained with a maximum degree of efficiency and economy in operation. I accomplish this object by means of the device hereinafter more specifically described, reference being had to the accompanying drawings forming part hereof, in which—

20 Fig. 1 is a vertical central section.

Fig. 2 is a section on line 2—2 of Fig. 1.

Referring to said drawings, 1 is a base upon which the fuel combustion unit is supported. The said base is provided with an annular chamber 2, to which gas is carried by the pipe 3, which is connected to any source of gas supply not shown, the walls of said chamber on the inner side thereof being provided with perforations 4, for the discharge of gas which, being ignited, produces a flame for the ignition of the fuel dropping through the perforations into the bottom of the troughs and falling from one trough to the other of the combustion unit.

35 The said combustion unit comprises a series of superimposed horizontally disposed annular troughs 5, being comparatively closely associated, forming passages or spaces therebetween. The said troughs are provided

40 with supports or legs 6, projecting from the lower sides thereof. The troughs are also provided with a number of perforations 7—7, formed in the bottom thereof, for the purpose of permitting the liquid fuel, such

45 as oil, to flow through said perforations and fall from the upper trough in a fine stream or film to the trough immediately below. The said base is also provided with a lip 9, which forms a drip pan for the reception of

50 any fuel that may be falling from the lowermost trough. The said drip pan may be provided with a suitable drain pipe controlled by a drain cock not shown, for the purpose of withdrawing the oil therein when

desirable. A member 10, hyperboliform in configuration, is centrally supported with said troughs and constitutes means for directing the ascending currents of air across the fuel in the troughs for the purpose of promoting combustion of the fuel therein, the said member having wings *a*, projecting from the sides thereof and forming channels for the guidance of the air which, ascending through said channels as shown by the arrows in Fig. 1, passes over the several fuel troughs and in its passage intermingling with the vaporizing gases from the combustion of the liquid fuel. The said member 10, encases or surrounds the fuel supply pipe 11, which is connected to or with any source of fuel supply not shown, the said fuel supply being as a matter of course at a plane above the top of the combustion unit. The said pipe 11, projects through said member 10, and is screw-threaded upon its upper end upon which a nut 12, is secured for the purpose of holding the several parts of the structure firmly together, a nut being on the lower end of the pipe against which the air conducting means is forced. This is the only fastening device necessary to secure all of the parts of the structure firmly together. The top or upper end of the structure is provided with a cap 13, the function of which is to prevent the air ascending vertically centrally of the device and to cause the same to traverse the various troughs as shown in the drawing.

It is noted that the outer edges of the several fuel troughs are inclined on an acute angle, for the purpose of directing the flame arising from the combustion of the liquid fuel in a transverse direction, making substantially a cylindrical column of flame.

Having described my invention, what I claim and desire to secure by Letters Patent is—

1. In an apparatus for the combustion of liquid fuel, the combination of a base, a series of superimposed cylindrically disposed troughs adapted to contain liquid fuel, the said troughs having perforations in the bottom whereby the fuel is adapted to drop from one trough to the trough immediately below, a drip pan arranged below the lowermost of said troughs, a cap closing the passage above said troughs, and means for directing the streams of ascending air across

and between said troughs, the said means including a member hyperboliform in configuration supported between said troughs.

2. In an apparatus for the combustion of liquid fuel, the combination of a base having an annular chamber therein, the inner wall of which is perforated and having a drip pan integral therewith, means to convey gas to said annular chamber, a series of super-
16 imposed cylindrically disposed troughs adapted to contain liquid fuel, the said troughs having perforations in the bottom whereby the fuel is adapted to drop from one trough to the trough immediately below,

a cap closing the passage above said troughs, means for directing the streams of ascending air transversely across and between said troughs, the said means including a member hyperboliform in configuration supported between said troughs.

In testimony whereof, I have hereunto signed my name in the presence of two subscribing witnesses.

20

SAMUEL TROOD.
